UNITED STATES PATENT OFFICE.

FRANK M. WOJCIECHOWSKI, OF NORTH ATTLEBORO, MASSACHUSETTS.

DESIGN FOR A VANITY CASE.

Application filed January 29, 1927. Serial No. 20,530. Term of patent 7 years.

To all whom it may concern:

Be it known that I, FRANK M. WOJCIECHOWSKI, a citizen of the United States, residing at North Attleboro, in the county of Bristol and State of Massachusetts, have invented a new, original, and ornamental Design for a Vanity Case, of which the following is a specification, reference being had to the accompanying drawings, forming part thereof.

The figure is a perspective view, the ornamentation of the obverse and the reverse being identical.

I claim:

The ornamental design for a vanity case, as shown.

In testimony whereof I have signed my name to this specification.

FRANK M. WOJCIECHOWSKI.
